(57) CLAIM

The ornamental design of a footwear, as shown and described.

DESCRIPTION

FIG. 1 is a front-right perspective view of the footwear, showing my new design;

FIG. 2 is a front view thereof;

FIG. 3 is a right side view thereof;

FIG. 4 is a left side view thereof;

FIG. 5 is a back view thereof;

FIG. 6 is a top view thereof;

FIG. 7 is a bottom view thereof;

FIG. 8 is a front-right perspective view of the footwear of FIG. 1 with the top part of the footwear reversed and folded down over the lower portion;

FIG. 9 is a right side view of the footwear of FIG. 8;

FIG. 10 is a front view of the footwear of FIG. 8;

FIG. 11 is a back view of the footwear of FIG. 8;

FIG. 12 is a left side view of the footwear of FIG. 8;

FIG. 13 is a top view of the footwear of FIG. 8; and,

FIG. 14 is a bottom view of the footwear of FIG. 8.

The central vertical line in FIG. 11, which is a dash-dot-dash broken line, is for illustrative purposes only and forms no part of the claimed design. All the other broken lines in the drawings indicate stitching.
